UNITED STATES PATENT OFFICE.

ARTHUR E. BURTCHELL, OF SAN FRANCISCO, CALIFORNIA.

CELL-CASE.

1,160,493.

Specification of Letters Patent. Patented Nov. 16, 1915.

Application filed July 14, 1914. Serial No. 850,867.

To all whom it may concern:

Be it known that I, ARTHUR E. BURTCHELL, a citizen of the United States, residing in the city and county of San Francisco and State of California, have invented certain new and useful Improvements in Cell-Cases, of which the following is a specification.

The present invention relates to improvements in egg case fillers, cell-cases or trays adapted for the packing of eggs or similar fragile articles for shipment, so that the same will not be subjected to the jar and rough usage in handling the container and become broken.

The invention has for its principal objects to provide a cell-case constructed in such a manner that the articles contained in one cell will be cushioned from those in adjacent cells and will not contact at the same points on the cell forming members; one which is capable of being folded into a small compass for shipment; one having a novel form of locking means for retaining the cell forming members in locked engagement, and one having a base member of novel form for coöperation with the cell forming members.

With the above mentioned and other objects in view, the invention consists in the novel construction and combination of parts hereinafter described, illustrated in the accompanying drawings and pointed out in the claims hereto appended; it being understood that various changes in the form, proportion, size, and minor details of construction within the scope of the claims may be resorted to without departing from the spirit or sacrificing any of the advantages of the invention.

To more fully comprehend the invention, reference is directed to the accompanying drawings wherein is disclosed one form of my invention, and in which—

Figure 1 is a view in plan of my invention, partly broken away, disclosing the cell forming members and one of the layer partitions. Fig. 2 is a sectional view taken on line 2—2 of Fig. 1. Fig. 3 is a view of the invention in extended and folded positions, shown by full and dotted lines respectively.

Fig. 4 is a view taken on line 4—4 of Fig. 1. Fig. 5 is a view of two intersecting cell forming members in their extended position and in dotted lines disclosing the same folded on each other. Fig. 6 is a view in detail of the lock forming slots in one of the members. Fig. 7 is a view in elevation of two of the intersecting cell forming members locked together.

Referring more particularly to the several views of the drawings, wherein like characters of reference designate corresponding parts throughout the several views, the numeral 1 indicates a suitable receptacle in which is positioned a suitable base or partition member 2 formed with the parallel spaced upstanding flat topped rib members 3, each preferably formed at spaced intervals with the circular openings 3', which are in this case adapted to receive the points of the eggs, as in Fig. 4. Resting on each of said base or partition members 2 are suitable cell cases arranged one above the other, and of a size to extend to all of the side walls of the receptacle. The cell cases consist of the parallel spaced longitudinally and transversely extending cell forming members 4 and 5, which intersect each other and which are preferably formed of cardboard or any other suitable pliable material.

Each cell forming member or strip consists of a plurality of substantially inverted S-shaped bends having the curved end portions 6 connected by diagonal shanks 6' and adjacent inverted S-shaped bends are united by straight sections 7 which are in line with each other, as in Fig. 5. The shank portions 6' of the longitudinal and transverse strips 4 and 5 are slotted respectively on their upper and lower edges, as at 8, these slots extend inwardly partly at an oblique angle to their respective edges, as at 9, and thence at a right angle thereto, as at 10, to a point approximately midway between the edges of the strips. In this manner a lateral locking tongue 11 having an inner face parallel with the outer edges of the strips is formed at the outer end of the slots, and these tongues project into and overhang suitable cuts 12 formed in the opposite edges of 100

the respective strips, thereby providing a locking means for securing the strips together at their intersecting points.

In assembling, the intersecting strips are arranged in such a manner that the curved end portions 6 will provide cushion members for each of the four sides of the respective cells, as in Fig. 1, and against which the article positioned in the respective cells will rest. It will be apparent by reference to Fig. 1, that the articles positioned in the respective cells do not contact with the same points on the strips as do the articles in adjacent compartments, and that each of the curved end portions 6 provide a yieldable cushion against which the articles rest.

The straight sections 7 of the transverse strips 5 extend below the lower edge of the remaining portion of the strip, thus forming tongues 13 which seat in the channels between the rib members 3 in the floor or partition members 2 and prevent the displacement or moving of the cell cases when packed in a receptacle and receiving articles.

By making the strips 4 and 5 of the same configuration and intersecting the same at right angles at the diagonal shank portions 6', it will be apparent by examining Figs. 3 and 5, that when it is desired to collapse the cell cases when disengaged from the base members, the curved end portions 6, shanks 6' and straight sections 7 of the longitudinal members will lie adjacent the same portions on the transverse members.

My improved cell case is capable of being collapsed to occupy but a small space when not in use, is also formed or fashioned to provide a cushion member on each of the four side walls of each cell, and the strips forming the cell case are provided with a locking means for securing the same together at their intersecting points.

Having thus described my invention what I claim and desire to protect by Letters Patent is:—

1. A collapsible cell case comprising longitudinal and transverse members forming a series of adjacent cells for the reception of articles to be shipped, each of said members consisting of a plurality of substantially inverted S-shaped sections connected together at their ends by aligned portions, and the shanks of said substantially inverted S-shaped sections extending diagonally of the longitudinal line of said members, said longitudinal and transverse members intersecting at the shank of each of said inverted substantially S-shaped sections.

2. A collapsible cell case comprising longitudinal and transverse intersecting members forming a series of adjacent cells for the reception of articles to be shipped, a base for

each cell case formed with parallel spaced ridges extending from one side edge thereof to another and provided with spaced apertures for the reception of the lower ends of the articles positioned in said cells, and tongues projecting from the lower edge of certain of said intersecting members for reception in the depressions between said ridges.

3. A cell case comprising longitudinal and transverse intersecting members forming a series of adjacent cells, each member provided with a series of spaced cushioning sections and a web therebetween, each cushioning section comprising cushioning beads connected by a shank portion extending diagonally to the plane of the web.

4. A cell case comprising longitudinal and transverse intersecting members forming a series of adjacent cells for the reception of the articles to be shipped, each member provided with a series of spaced cushioning sections and a substantially straight web therebetween, each cushioning section comprising oppositely disposed bearing beads connected by a shank portion extending diagonally to the plane of the substantially straight web.

5. A cell case comprising longitudinal and transverse members forming a series of adjacent cells for the reception of articles to be shipped, each of said members consisting of a plurality of substantially inverted S shaped sections connected together at their ends by substantially straight web portions.

6. A collapsible cell case comprising a plurality of longitudinal and transverse intersecting members forming a series of adjacent cells for the reception of articles to be shipped, each of said members being formed with cushioning means for the walls of the cells, the said cushioning means adapted to interfit upon the folding of the cell case, so that the cell case when folded is substantially flat.

7. A collapsible cell case comprising longitudinal and transverse intersecting members forming a series of adjacent cells for the reception of articles to be shipped, each of said members being formed to provide cushioning means for the walls of the cells, the cushioning means of the longitudinal members interfitting the cushioning means of the transverse members on the folding of said cell case.

8. A collapsible cell case comprising longitudinal and transverse intersecting members forming a series of adjacent cells for the reception of articles to be shipped, each of said members being formed to provide cushioning beads for the walls of the cells, all of said cushioning beads adapted to interfit upon the folding of the cell case.

9. A cell case comprising longitudinal and transverse intersecting members forming the walls of a series of adjacent cells for the reception of articles to be shipped, each side wall of each cell being provided with a single bead, the bead of one wall being offset with reference to the bead of the opposite wall to dispose them near the corner portions of the cell, to constitute a four-point cushioning means for the article within the cell, 10 which leaves the article otherwise free.

In testimony whereof I have signed my name to this specification in the presence of two subscribing witnesses.

ARTHUR E. BURTCHAELL.
